UNITED STATES PATENT OFFICE

171,565

SAFETY TOOL FOR PRESSURE TANK CARS

Emil E. Wickman, Orinda, Calif.

Application March 2, 1953, Serial No. 23,830

Term of patent 14 years

(Cl. D54—13)

To all whom it may concern:

Be it known that I, Emil E. Wickman, a citizen of the United States of America, residing at Orinda, Contra Costa County, State of California, have invented a new, original, and ornamental Design for a Safety Tool for Pressure Tank Cars, of which the following is a specification, reference being had to the accompanying drawing forming a part hereof.

Figure 1 is a top plan view of a safety tool for pressure tank cars showing my new design;

Figure 2 is a side elevational view thereof;

Figure 3 is an elevational view showing the bottom end of Figure 2;

Figure 4 is an elevational view showing the left end of Figure 2;

Figure 5 is an elevational view showing the right end of Figure 2; and

Figure 6 is a perspective view of the device.

I claim:

The ornamental design for a safety tool for pressure tank cars, substantially as shown.

EMIL E. WICKMAN.
